UNITED STATES PATENT OFFICE.

HOSEA H. HUNTLEY, OF QUINCY, ILLINOIS.

IMPROVEMENT IN STEAM-BOILER FURNACES.

Specification forming part of Letters Patent No. **82,841**, dated October 6, 1868.

To all whom it may concern:

Be it known that I, HOSEA H. HUNTLEY, of Quincy, in the county of Adams and State of Illinois, have invented a new and valuable Improvement in Furnaces; and I do hereby declare that the following is a full, clear, and exact description of the construction and operation of the same, reference being had to the annexed drawings, making a part of this specification, and to the letters and figures of reference marked thereon.

The nature of my invention consists in constructing a furnace in such form and manner as to admit heated air to the fire, thereby greatly intensifying the heat and consuming the smoke by first changing said air and smoke into inflammable gas.

The letters A of the drawings represent the fire-places, separated by the air-chamber B.

Letters C are grate-bars below the fire. These bars are made in a tubular form, with flattened upper surfaces.

Letters D are small apertures in the front end of the furnace, through which cold air passes into the grate-bars. Similar apertures in the plate at the rear end of the grate-bars admit the air from the bars to the conical chamber E. These last-named apertures are marked F.

Letter G is an air-passage leading into the air-chamber B. This air-chamber is divided by a plate, *a*, which separates it into an upper and lower chamber. The plate *a* extends from the rear of said chamber to within about two inches (more or less) of the front thereof.

The upper compartment of chamber B is perforated with holes in its sides to allow the air, when heated therein, to pass to the fire.

The letters H are air-chambers on each side of the fire-place, and they also are perforated on their sides next the fire to provide for the passage thereto of heated air. There are also similar air-passages from the surface of the conical chamber E.

Letters K are tubes for the admission of cold air to the chambers H, respectively.

Immediately in the rear of the chamber B, and adjoining the conical chamber E, I adjust the conical chamber L, which extends rearward to a point near the back end of the furnace. The extreme rear end of chamber L is left open to receive the air from the chamber M, next mentioned.

The letter M is an air-chamber extending from the top of the furnace to the plate *c*, which said plate is on a level, or nearly so, with the grate-bars.

The letters O are tubes that convey cold air to the chamber M. The side of chamber M next the fire is perforated, as shown, to admit of the passage therefrom of the partially-heated air into the air-space shown in the rear of chamber E, and from said air-space to the fire.

My device operates as follows: When the fire is built and the draft arising therefrom begins to move the atmosphere the cold air passes into the apertures D, passage G, and tubes K and O, and as the several chambers connected with the said conduits become warm and hot the air in said chambers is drawn to the fire in a heated condition. The result is a thorough superheating of the air, a precipitation of the hydrogen and carbon into inflammable gas, which passes off in the combustion, thereby not only preventing smoke, but also adding materially to the heat of the fire.

What I claim as my invention, and desire to secure by Letters Patent, is—

A furnace having grate-bars C, with apertures D, passage G, tubes O and K, and chambers B, H, L, and M, constructed, arranged, and operating substantially as specified.

HOSEA H. HUNTLEY.
